JAMES R. LOGAN, OF BELLMORE, INDIANA.

Letters Patent No. 66,602, dated July 9, 1867.

IMPROVEMENT IN SAWING MACHINES.

The Schedule referred to in these Letters Patent and making part of the same.

TO ALL WHOM IT MAY CONCERN:

Be it known that I, JAMES R. LOGAN, of Bellmore, in the county of Park, and State of Indiana, have invented a new and improved Sawing Machine; and I do hereby declare that the following is a full, clear, and exact description thereof, which will enable those skilled in the art to make and use the same, reference being had to the accompanying drawings, forming part of this specification, in which—

Figure 1 is a plan or top view of my invention.

Figure 2, a side sectional view of the same taken in the line *z z*, fig. 1.

Figure 3, a transverse vertical section of the same taken in the line *y y*, fig. 1.

Similar letters of reference indicate corresponding parts.

This invention relates to an improvement on a new and improved cross-cut sawing machine for which Letters Patent were granted to me bearing date December 19, 1865. The within-described improvement consists in a peculiar construction of the carriage on which the machine is mounted, whereby the frame of the machine may be retained in a horizontal position when placed on uneven or inclined ground. The improvement also consists in a modification of the construction of the standard or support to which the saw-bar is attached when sawing felled timber, and further, in the employment or use of a saw-guide, all arranged as hereinafter set forth.

A represents a rectangular frame, the rear part of which is supported by two wheels *B B*, the axle *C* of which is of double-inclined form, as shown in fig. 3, its upper surface being highest at the centre. On this upper surface of the axle a transverse bar, *a*, of the frame *A* rests or bears. The under surface of this bar *a* is of double-inclined form, it being thickest at the centre, and the frame *A* is secured to the axle *C* by a bolt, *b*, passing centrally through *a* and *C*. *D D* represent thills or shafts attached to the frame *A*; and *E* is a bar which is framed into the rear end of the frame *A*, extends upward a suitable distance, and is then bent over in a forward direction, and has its front end secured to the front cross-piece *c* of the frame *A*, as shown clearly in fig. 2. This bar *E* may be of wood, and, in consequence of being constructed and applied as shown, is rendered very stiff and firm, and is well calculated to support the bar *F*, which, when the saw is cutting felled timber, works on a pin, *d*, projecting from the bar *E*, as shown in figs. 1 and 2. The saw-bar *G* is attached to the end of the bar *F* in the same way as described in the original patented machine, and the bar *F*, when standing timber is to be sawed down, is placed in a horizontal position on the frame *A*, and works on a pin, *f*, at either side thereof, the saw in the latter case being fed to its work by a spring in a block, *H*. This arrangement is precisely the same as the original, with the exception that a weight, *g*, may be connected with or used as an auxiliary to the spring. The axle *C* has a vertical pin, *h*, attached to it near each end, and these pins pass up through oblong slats *i* in the cross-bar *a*, and serve as guides for the frame of the machine. This manner of fitting the frame *A* on the axle *C* is a great improvement, as the machine frequently is required to stand upon inclined ground, and, when this is the case, the machine may be kept in a horizontal position. *I* is a guide attached to or fitted in the front cross-piece *c* of the frame *A*, said guide being composed of a bar slotted vertically for the saw-bar *G* to work through. The bar *F* is operated by a pitman, *J*, from a crank-shaft, *K*, as hitherto.

Having thus described my invention, I claim as new, and desire to secure by Letters Patent—

Allowing the frame of the machine to conform to any inclination of the log, by means of the slotted transverse bar *a* resting on axle *C*, provided with pins *h*, constructed as described, and operating substantially in the manner and for the purpose specified.

JAMES R. LOGAN.
